KNITTED FABRIC AND METHOD OF PRODUCING SAME

Arthur J. Reinthal, Cleveland Heights, Ohio, assignor to The Bamberger-Reinthal Company, Cleveland, Ohio, a corporation of Ohio

Application November 30, 1936, Serial No. 113,369

2 Claims. (Cl. 66—195)

This invention relates to a knitted fabric and method for producing the same, and has particular reference to a fabric having an elastic zone suitable for waistbands, cuffs and the like.

An object of the invention, broadly stated, is to provide a fabric comprised of unit groups of yarns that interloop to form the fabric and with one or more yarns of each group being, in one zone of said fabric inelastic, and, in another zone, elastic, and such fabric being of essentially uniform thread pattern in both zones, whereby to be produced by the same machine setting as if the entire fabric were of either elastic or inelastic construction. By the use of the expression "essentially uniform thread pattern" I do not intend to limit myself to the production of a fabric in which the thread pattern is actually uniform throughout but only to one in which no non-uniformity of thread pattern is introduced for the purpose of producing the elastic zone. In other words, my invention contemplates a fabric in which the thread pattern may vary in different parts for the production of pleasing effects but in which the elastic zone is produced by the substitution of elastic yarn for inelastic yarn without change in the thread pattern for the purpose of securing elasticity.

A further object is to produce such fabric by beaming the warp in unit groups of yarns with the corresponding yarns of each unit being in one group of units elastic and in another group inelastic, the elastic yarns being placed under a higher tension in the beaming operation than the inelastic yarns, whereby no change need be made in subsequent operations by reason of the presence of the elastic yarns under high tension; that is, the elastic yarns are fed from the beam at the same rate as the other yarns and the set-up of the knitting machine need be no different in those cases where a fabric is made with an elastic zone from those where the entire fabric is inelastic. While the feature of placing the elastic yarns under higher tension than the inelastic ones is an important feature of the invention, it is nevertheless within the contemplation of the invention to employ yarns of such elastic nature that they may be subjected to the same tension in the beaming operation as the inelastic yarns and fed from the beam to the knitting machine at the same rate.

By the expression "beaming" as herein used, it is intended to include the operations of winding yarns from the cones under suitable tension upon a reel and then again winding the yarns from the reel upon a beam which is then placed in

position upon the knitting machine. The difference in tension applied to the elastic yarns is preferably applied in the process of transferring the yarns from the cones to the reel. This may be done by a snubbing action, as will be brought out hereinafter. The elastic yarns may consist of filaments of rubber spirally wound with one or more yarns which are not elastic per se whereby the stretch of the composite elastic yarn is limited. By the term "yarn" as used in the claims is meant either a single thread or a plurality thereof running together.

Other and more limited objects will be in part apparent and in part pointed out hereinafter in connection with the accompanying drawings wherein Fig. 1 is a front view of a sweater or like garment having elastic zones at the waistband and cuffs; Fig. 2 is a fragment of a fabric showing the elastic zone stretched to the same shape as the inelastic zone, and with both zones under tension, as for example, in the portion of fabric being wound on a receiving roll as it comes from the knitting machine; Fig. 3 is a similar fragment with the tension relieved; Fig. 4 is a schematic diagram showing one thread pattern which may be employed in realizing the invention; Fig. 5 is a fragment showing the same thread pattern in a less schematic manner, although expanded to a degree of openness and geometric form not present in the fabric itself; and Fig. 6 is a schematic diagram illustrating the difference in tensioning which is made use of in the reeling part of the beaming operation. Figs. 4 and 5 show the wales running horizontally.

Referring now to the drawings, the numeral 10 indicates a knitted garment made up of a fabric produced in accordance with the invention and indicating the shape resulting from the incorporation of the invention. The garment has 40 elastic zones at the waistband as indicated at 11 and at the cuffs, as indicated at 12. This garment may be made from a fabric which comes from the knitting machine in a strip of the shape indicated in Fig. 2 by reason of being under tension and comprising an inelastic zone 10^a and an elastic zone 11^a at the edge. When the tension is removed, the elastic zone contracts in length, as indicated in connection with the left hand end of the same shown in Fig. 3, wherein the same numerals indicate corresponding portions of the fabric shown in Fig. 2.

In the circular type of knitting machine, where the knitting progresses by the intertwining of a yarn with a preceding run in a direction trans-

versely of the direction of progress of the fabric through the machine, it is comparatively easy to introduce an elastic yarn or a group of yarns having one elastic yarn therein by merely picking up a different yarn carrier at the point where the elastic is to be inserted. The tension here may be individually regulated for the yarn, fed from each yarn carrier so that the substitution of an elastic yarn under any desired tension for 5 an inelastic yarn is a comparatively simple matter. However, where the yarn is supplied from a beam and runs longitudinally of the direction of the progress of the work through a machine, the machine set-ups are comparatively complex 10 15 and it is highly desirable that the setting of the machine be unaltered for long periods of operation. Heretofore, in knitting fabrics having elastic zones on what may be termed the beam type of machine, an additional thread has been 20 introduced or superadded to the regular thread pattern in the elastic zone. While this partially solves the problem, it does not do so completely. Also, if involves the use of the regular yarn in addition to the elastic strands, which introduces 25 an item of expense beyond that prevailing where a substitution is made. Indeed, the prevailing practice has been to knit the elastic zones separately and attach them after the knitting has been completed.

30 I have found in practice that by introducing a predetermined proper tension during the beaming operation, I am able to produce a satisfactory product in a cheaper and more desirable manner and to effect a simple substitution of an elastic 35 40 for an inelastic thread in the same thread pattern and to knit the fabric with an elastic zone without any change whatsoever in the knitting machine.

In Fig. 6, I have shown one unit group of yarns 45 proceeding from the cones (not shown) to snubbing rods 13, the yarn *b*, an elastic yarn in the elastic zone of the fabric, passing first around an additional snubbing rod 14, while the yarns *a*, *c* and *d* pass around only snubbing rod 13. 50 From the snubbing rods 13, the yarns pass to a 45 55 60 yarn guide 15 where they are positioned in suitable relation to each other and from which they pass to a reel 16 upon which they are wound. It is to be understood that the unit group of yarns shown in Fig. 6 is repeated a plurality of times 55 60 65 in filling a single beam for actual use. It is not necessary to use the snubbing rod 14 in the inelastic zone since in that zone the elastic yarn is not used for the yarn *b* and the extra snubbing 70 would be without utility and in the case of some 75 80 85 yarns even undesirable. From the reel 16 the yarns are unwound upon a suitable beam, all yarns being fed at the same rate from the reel 16 to the beam. The beam is then placed on the knitting machine and the yarns knitted into the complete fabric.

In Figs. 4 and 5, I have shown a thread pattern which is an example of the type in which my invention may be realized and wherein, as will be clear from the drawings, a unit group of four yarns is employed. In Fig. 5, yarn *a* is

omitted for clearness and, in some cases, it may be omitted in the fabric itself, it being used primarily to limit stretching in a direction transversely of the progress of the work through the knitting machine. It will be seen by reference to Fig. 5 that two types of interlooping are employed. These form ribs of different types which alternate and which are indicated by the reference characters *A* and *B*. Intertwined with the loops of the *A* type ribs are yarns *b* which are 10 confined to such ribs. These are elastic in the elastic zone or zones and are inelastic in the inelastic zone. In other words, it is the yarns *b* which may be made either elastic or inelastic whereby to produce a fabric having zones of different elasticity while maintaining a uniform thread pattern and necessitating no change in the knitting machine. The yarn *a* may run diagonally back and forth between the *A*-type ribs, 15 20 25 passing over the *B*-type ribs which tend to greater stretching. This is clearly shown in the diagrammatic view in Fig. 4.

In Fig. 5, which shows a very small fragment of the fabric, no attempt has been made to differentiate the elastic from the inelastic yarn. 25 However, in Fig. 4 the yarns *b* in the elastic zone have been indicated by heavy lines while those in the inelastic zone have been indicated by relatively light lines.

From the foregoing description and the accompanying drawings, it will be clear that I have provided a knitted fabric of satisfactory and highly economical construction and a satisfactory method of producing the same, and while I have shown and described the illustrative embodiments 30 35 40 45 50 of the various features, I do not wish to be limited to the details of the disclosure, but only in accordance with the appended claims.

Having thus described my invention, what I claim is:

1. Process of making a knitted fabric comprising beaming a warp composed of unit groups of yarns, corresponding yarns of each unit being in one group of units elastic and in another group inelastic, said elastic yarns being under 45 higher linear strain than the others on the beam, fabricating the yarns making up both said groups of units in a uniform thread pattern, the corresponding yarns of each unit being fed from the beam at the same rate whereby a fabric is produced having a compact highly elastic zone and a less compact inelastic zone.

2. Process of making a knitted fabric comprising beaming a warp composed of groups of yarns, one or more yarns of each group being in one 55 zone of the warp elastic and in another zone thereof inelastic, said elastic yarns being put under higher linear strain than the others on the beam, knitting the yarns of both zones into an essentially uniform thread pattern, the corresponding yarns of each unit being fed from the beam at the same rate whereby a fabric is produced having a compact, highly elastic zone and a less compact and relatively inelastic zone.

ARTHUR J. REINTHAL.
